(57) **CLAIM**

The ornamental design for a cryoelectrolysis ablation device, as shown and described.

DESCRIPTION

FIG. 1 is a perspective view of an embodiment of a cryoelectrolysis ablation device in accordance with the present invention;

FIG. 2 is a second perspective view of the cryoelectrolysis ablation device of FIG. 1;

FIG. 3 is a front view of the cryoelectrolysis ablation device of FIGS. 1 and 2;

FIG. 4 is a back end view of the cryoelectrolysis ablation device of FIGS. 1-3;

FIG. 5 is a side view of the cryoelectrolysis ablation device of FIGS. 1-4;

FIG. 6 is a second opposite side view of the cryoelectrolysis ablation device of FIGS. 1-5;

FIG. 7 is a top view of the cryoelectrolysis ablation device of FIGS. 1-6;

FIG. 8 is a bottom view of the cryoelectrolysis ablation device of FIGS. 1-7; and,

FIG. 9 is a perspective view similar to FIG. 2 of the cryoelectrolysis ablation device but with a screen portion in a second position.
The broken line shown in the drawings is included for the purpose of illustrating portions of the cryoelectrolysis ablation device and forms no part of the claimed design.
